G. O. ESKELAND

ROLLER SKATE

Filed March 11, 1925

INVENTOR
GUNNAR O. ESKELAND
BY
Richard J. Cook
ATTORNEY

UNITED STATES PATENT OFFICE.

GUNNAR O. ESKELAND, OF SEATTLE, WASHINGTON.

ROLLER SKATE.

Application filed March 11, 1925. Serial No. 14,638.

This invention relates to improvements in skates and more particularly to roller skates of the two or three roller type; it being the principal object of the invention 5 to provide skates of the above character wherein the rollers are supported through the intermediacy of shock absorbing springs.

Another object is to provide skates having the rollers arranged in the central longitudinal line of the skate as distinguished from being arranged in pairs as is ordinary practice.

A still further object resides in the provision of means whereby the skate may be 15 adjusted to different lengths and secured at the different positions of adjustment.

Another object resides in the provision of a three-roller skate wherein the central roller is mounted slightly below the line of 20 the two end rollers in order that only two rollers of the skate will be in contact with the floor at a time.

Other objects reside in the details of construction and combination of parts whereby 25 the toe and heel sections are joined rigidly substantially and adjustably together.

In accomplishing these and other objects of the invention, I have provided the improved details of construction, the preferred 30 forms of which are illustrated in the accompanying drawings, wherein—

Figure 1 is a side view of a three-roller skate embodying the present invention.

Figure 2 is an under side plan view of 35 the same.

Figure 3 is a transverse section taken through a roller and its supporting bearings.

Figure 4 is an enlarged, transverse section taken on the line 4—4 in Figure 1.

40 Figure 5 is an enlarged, transverse sectional view showing the clamping means whereby the skate may be secured to the sole of a shoe.

Figure 6 is a side view of a two-roller 45 skate.

Referring more in detail to the several views of the drawings—

1 and 2, respectively, designate the heel and toe plates of the skate which are joined 50 adjustably and held rigidly in functional relation by means of two overlapping ribs 3 and 4; the former of which is secured centrally beneath and longitudinally of the heel plate and is adapted to slide upon the 55 rib 4 which is secured likewise to extend

rearwardly from the toe plate. Each of these ribs 3 and 4, as is shown best in Figure 3, has a flat central portion from which flanges are turned downwardly along opposite sides. Rivets 5 and 6 are extended respectively through these flanges and through parts that support the roller, presently described, to hold the ribs rigid. The former portion of rib 3 is adapted to move telescopically between the upper side of rib 4 and under face of the toe plate 2, and its flanges slide upon the flanges of the rib 4 and within the upturned edge portions 4^a of the latter, as is shown best in Figure 4. The central portions of the ribs 3 and 4 are provided with longitudinally directed and registering slots 7 or provided with a series of registerable apertures and the heel plate with an opening 8 through which a set screw 9 is extended and which has a nut 9' adapted 70 to be tightened to lock the parts at the different positions of adjustment that may be made.

Secured to the under sides of the heel and toe plates are roller mountings; those of the heel plate being for a single roller and comprises two metal housings 10 and 10' secured by rivets 11 through outturned flanges 12 along their upper edges. These housings are disposed in spaced relation and a roller 13 is mounted between them on a transverse shaft 14, the ends of which extend through slots 15 in the housings and are mounted in blocks 16 that are adapted to move slidably in upwardly and forwardly directed 80 guideways 17 formed by the housings. Coiled springs 18 are contained in the housing guideways, and these bear against the upper ends of the blocks 16 to yieldably resist their upward movement and thereby absorb all shock and jar on the roller. The roller is rotatably mounted on the cross shaft through the intermediacy of a double set of ball bearings, as shown at 20, and is spaced to prevent rubbing contact with the 85 housings by means of washers 21 at its opposite sides.

Secured to the under face of the toe plate are housings 22 and 22' for mounting two rollers 24 and 25 in a line centrally of the plate and in line with the heel plate roller. The central roller 24 is disposed somewhat below the line of the two end rollers in order that only two rollers will contact with the floor at the same time. These rollers are 100 105 110

mounted on axles 26 and 27, mounted similarly as the rear roller previously described; the axle 26 being fixed at its ends to blocks 28 operating in guideways 29 and axle 27 is 5 fixed to blocks 30 operating in guideways 31 and the guideways 29 and 31, at opposite sides of the rollers, are inclined upwardly and toward each other as shown in Figure 1.

Secured to the rear edge of the heel plate 10 is a retaining flange 35 for holding the skate properly on the heel of the user and secured to the toe plate are clamps 36 and 37 for engaging opposite edges of the sole of the shoe of the user. These clamps are connected by and may be adjusted by the rotation of a right and left hand screw 38 as is provided on skates now in use.

In Figure 6, as shown a two roller skate differs from the one just described in that 20 the toe plate has only one roller attached thereto, this skate being more suitable for children's use.

With a skate of the above character, it is 25 possible to adjust it to suitable length by loosening the nut 9' and adjusting the ribs 3 and 4 upon each other. The adjustment may be retained then by tightening the nut.

It is also apparent that by the use of the 30 spring mountings for the rollers, all shock or jar is absorbed and an easy, cushioning effect is provided.

Having thus described my invention, what

I claim as new therein and desire to secure by Letters Patent, is:

1. In a skate of the class described, a heel 35 plate, a toe plate, rollers mounted on said plates, a rib fixed to the heel plate and extended forwardly thereof having a slot therein and having downturned flanges along its side edges, a rib fixed rigidly to 40 the toe plate to extend rearwardly therefrom and adapted to be overlapped by the first named rib and having a slot therein and having downturned flanges along its side edges with upturned edges forming 45 channels wherein the flanges of the first named rib are adapted to fit and a locking bolt extended through said rib slots to lock the same together at different positions of adjustment.

2. In a skate of the class described comprising relatively adjustable heel and toe plates, a series of supporting rollers mounted in alignment centrally beneath said plates comprising a forward roller, a rearward 55 roller and a central roller; the latter being mounted slightly below the line of the two end rollers, all of said rollers being provided with yieldable mounting bearings which permit the rollers to align with each other when 60 sufficient weight is placed on the skate.

Signed at Seattle, King County, Washington, this 11th day of February 1924.

GUNNAR O. ESKELAND.
